UNITED STATES PATENT OFFICE.

EDWARD R. IVES, OF BRIDGEPORT, CONNECTICUT, ASSIGNOR TO IVES,
BLAKESLEE & CO., OF SAME PLACE.

DESIGN FOR A TOY PISTOL.

SPECIFICATION forming part of Design No. 12,990, dated June 20, 1882.

Application filed May 1, 1882. Term of patent 7 years.

To all whom it may concern:

Be it known that I, EDWARD R. IVES, of Bridgeport, in the county of Fairfield and State of Connecticut, have invented a certain 5 new and original Design for a Toy, of which the following is a specification.

The toy shown in the accompanying drawing is suitable for use in exploding paper caps or fulminates; but the design is not confined 10 to such a toy.

The design consists of a base-piece and a figure of a mule kicking at a human being, both mounted on said base-piece.

The design also consists in a hammer for a 15 toy adapted for exploding caps and fulminates, made of such form as to bear a resemblance to a mule.

The design also consists in a cap or fulminate receptacle for a toy adapted for exploding caps and fulminates, made in the form 20 of a human being in a stooping posture.

The design also consists in a toy for exploding caps and fulminates, having a hammer made of such form as to bear a resemblance 25 to a mule and a cap or fulminate receptacle made in the form of a human being.

The accompanying drawing represents a side view of a toy embodying my design. The hammer is shown in one position in bold 30 outline and in another position in dotted outline.

A designates the hand-piece of the toy, which is made in the form of a pistol, and which constitutes a base-piece for the figures. 35 B is the hammer, which is made of such form as to bear a resemblance to a mule and is susceptible of a movement which causes it to simulate the kicking of such an animal.

C designates the cap or fulminate receptacle, made in the form of a man in a stooping 40 posture.

The whole design of the toy will be provocative of much mirth.

What I claim as my design, and desire to secure by Letters Patent, is—

1. The design consisting of a base-piece and a figure of a mule kicking at a human being, both mounted on said base-piece, substantially as specified.

2. The design consisting in a hammer for a 50 toy, adapted for exploding caps and fulminates, made of such form as to bear a resemblance to a mule, substantially as specified.

3. The design consisting in a cap receptacle for a toy, adapted for exploding caps and fulminates, made in the form of a human being 55 in a stooping posture, substantially as specified.

4. The design consisting in a toy for exploding caps and fulminates, having a hammer made of such form as to bear a resemblance to a mule, and a cap receptacle made in the form of a human being, substantially as specified.

5. The design consisting in a toy for exploding caps and fulminates, having a pistol-shaped hand-piece, a hammer made of such form as to bear a resemblance to a mule, and a cap receptacle made in the form of a human being, substantially as specified.

EDWARD R. IVES.
